CLAIM

The ornamental design for an accessory hose storage rack, as shown and described.

DESCRIPTION

FIG. 1 is a rear, perspective view of an accessory hose storage rack showing my new design;

FIG. 2 is an enlarged front elevational view thereof;

FIG. 3 is an enlarged rear elevational view thereof;

FIG. 4 is an enlarged left side-elevational view thereof;

FIG. 5 is an enlarged right side-elevational view thereof;

FIG. 6 is an enlarged top plan view thereof; and,

FIG. 7 is an enlarged bottom plan view thereof.

The broken line showing of an upright cleaning machine and accessory cleaning tool in FIGS. 1-7 for illustrative purposes only and forms no part of the claimed design.
